(57) **CLAIM**

The ornamental design for a tire tread, as shown and described.

DESCRIPTION

FIG. 1 is a perspective view of a tire tread showing our new design; and,

FIG. 2 is a front view thereof.

The broken lines in FIGS. 1 and 2 illustrate portions of the tire tread and environment that form no part of the claimed invention.

1 Claim, 2 Drawing Sheets

FIG. 1

FIG. 2
